METHOD OF MANUFACTURING
LOOM REEDS

Waldo H. Fish, Central Falls, R. I.; Myron C. Fish and Florence E. Fish, executors of said Waldo H. Fish, deceased

Application May 25, 1934, Serial No. 727,436

13 Claims. (Cl. 29—170)

My invention relates to improvements in the method of manufacturing loom reeds.

Prior to my invention loom reeds have consisted of two different general classes, namely, (1) a pitch band or cotton and woolen reed and (2) an all metal or silk or rayon reed.

An object of my invention is to provide a reed particularly suitable for weaving finer classes and grades of yarn, such as silk and rayon yarn which will have all the advantages of an all metal reed and certain features of flexibility of the cotton or woolen reeds added thereto. Broadly speaking, my invention provides a loom reed comprising dents, means for rigidly securing the ends 10 of said dents together at predetermined spaced intervals and resilient dam means interposed between each dent inside of said rigid joining means near each end thereof instead of the customary wire springs employed in an all metal construction.

An object of my invention therefore is to provide a loom reed having the advantages of the rigid accurate spacings of the silk reed and in a measure the resiliency of the pitch reed.

A pitch band or cotton and woolen reed as it is called in the trade has for its composition, dents, complementally semi-circular wooden ribs placed on each side of the dents near each end thereof and pitched yarn wrapped around said wooden ribs to flexibly secure said dents together and end bars if desired. Standard types of machines have been developed for making these pitch band reeds, in which the dent wire is fed between the spaced wooden ribs cut to its proper length and a strand of pitch yarn is spirally wound around said ribs between each dent wire and so on until a given length of reed is made. The reed is then removed from the machine, the end bars fastened at each end and the reed then completed by hand.

The construction of an all metal reed is a much more complicated matter than the manufacture of a pitch band reed. First the dent wire is temporarily set between wooden ribs with plain untreated cord. The reed is next counted so that the correct number of dent wires is assured. The correct size of the spacing wire is then figured, which when coiled as a spring and placed in the reed between the dent wires will give the correct number of dents per inch and a spring is placed in the reed near each end of the dents and after the spring is inserted, the cord band is cut from the wooden ribs and the wooden ribs and cord are removed. Other temporary spacing springs are now placed on the reed and moved to their respective places in the reed. Metal

strips are now fixed to the sides of the ends of the reed beyond said springs and a paste is applied to the spaces between the dents for the purpose of preventing the solder from running onto the metal surface of the dent wires through 5 said springs to the center portion thereof. Flat wooden boards may then be attached on each side of the reed with their ends terminating at the center portions of the wire springs to form a tight fit to prevent solder seeping around said wires. 10 The metal reed is then dipped in solder. The reed is then washed in water and finally brushed to rid it of the paste and any traces of the acid soldering flux. This is very important in that any trace of acid which might remain on the 15 dents will cause the wire to rust at the point where the spring comes in contact with it, which will eventually cause the wire to break at this point and ruin the reed.

My invention therefore is a novel method of 20 manufacturing a novel type of reed generally similar to the old so-called metal reeds heretofore described.

An object of my invention is to interpose a permanent resilient dam means of a general type 25 similar to the old pitch band in place of the wire spring to form the base of a solder well, the sides thereof being formed by the metal frame side bars affixed to each side of each dent near each end thereof. I have discovered that if this 30 resilient dam means be made out of suitable material it will absolutely prevent the soldering acids or the solder from passing through it to the center portions of the dents and will thus eliminate the expensive paste hitherto employed to 35 prevent the solder and soldering acid from seeping through as in the former metallic springs of the so-called metal reeds. This resilient dam means performs a double function of acting as a dam to prevent the soldering acid or solder from 40 seeping through in the manner hitherto described and also imparts the resiliency of the pitch band to this type of metallic frame to act as a buffer and to give more freedom of movement than the former rigid types of springs which 45 were formerly rigidly soldered to the dents at the base of the solder wells and thus by interposing this resilient means between each dent, providing it with an additional resiliency hitherto unknown in the general type of all metal reeds. 50 In place of the wooden bars of the usual pitch band reed, I substitute metal bars preferably half round-bars with their flat sides abutting the reeds which will not be affected by the soldering heat. While pitch may be employed I have found in use 55

that the heat of soldering will tend to melt it and it will tend to run down or seep between the dents and harden and so for this purpose I preferably employ a substance which has an intrinsic 5 capillary affinity for the absorbent cord when plastic so that as it is hardening it will be immediately attracted to the cord to harden even if it may melt somewhat and slip down the dents temporarily as the solder is employed and I 10 preferably employ wax for this purpose.

An object of my invention therefore is to provide not only a novel method of making a loom 15 reed of the so-called all metal type in a simpler manner than heretofore, but also to make a loom 15 reed of this description in which the dents are accurately spaced and which provides such a loom 15 reed with some of the resiliency of the pitch band 15 cotton or woolen reeds heretofore employed.

These and such other objects of my invention 20 as may hereinafter appear will be best understood from a description of the accompanying drawings, which illustrate an embodiment thereof.

In the drawings, Fig. 1 is a diagrammatic view 25 partially shown in section illustrating the method of impregnating my improved spacing cord with wax, a suitable acid-proof plasticizable material.

Fig. 2 is a side elevation of the initial step in 30 the manufacture of my invention which consists in assembling the dents in reed form with the approximate desired spacings and winding the absorbent cords coiled around metal ribs on each side of said dents near each end thereof with a coil thereof interposed between each dent.

Fig. 3 is a side elevation illustrating the third 35 step in my improved method which consists of temporarily spacing said dents to the desired spacings by interposing single winds of coil springs of predetermined size parallel to said 40 wound cord between said dents to provide said desired spacings.

Fig. 4 is a side elevation of a partially formed 45 reed in which the frame side bars have been temporarily secured to the dent ends by means of 50 wire and the frame end bars temporarily secured to the ends of said reed by the temporary spring mounting bars.

Fig. 5 is a sectional view taken along the line 55 5-5 of Fig. 4.

Fig. 6 is a sectional view illustrating how each 60 side end of my improved reed is dipped in a suitable solder bath and preferably raised to a horizontal position to permit the solder to become impregnated within the well thereof.

Fig. 7 is a perspective view of an improved reed 65 constructed in accordance with my invention.

In the drawings, wherein like characters of 70 reference indicate like parts throughout, 10 generally indicates a loom reed constructed in accordance with my invention.

As shown in Fig. 7, said improved loom reed 75 10 comprises the usual spaced dents 12 provided with rigid means 14 securing the ends of said dents together and resilient dam means 16 interposed between each dent inside of said rigid 80 joining means 14 near each end thereof, the rigid means 14 comprising the frame side bars 18 and frame end bars 20 rigidly soldered to each other by the solder 22 and to the ends 23 of each dent. It is thus apparent that in the finished product the rigid means 14 rigidly secures the ends of the dents together at the desired spaced 85 intervals and that the resilient dam means 16 interposed between each dent will provide a cer-

tain resiliency in the dents not common in former types of all metal reeds.

A further feature of my invention resides in the fact that the machines for making pitch band cotton or woolen reeds may be employed 5 in the manufacture of my improved all metal reed.

To provide said dam means as shown in Fig. 1, I preferably impregnate a cord 24 with a preferably plasticizable, acid-proof material 26 prefer-

ably having an intrinsic capillary affinity for said absorbent cord when plastic to form a covering 28 around said cord. As this material I preferably employ wax, such as paraffin wax, although it is obvious that other waxes, certain heavy oils, rub-

ber, rubber latex, certain synthetic or natural resins, tallow or other equivalent substances having these same general characteristics may be employed.

If desired, however, pitch may be employed, but I have found in use that this is not 20 so desirable as it does not when plastic have an intrinsic capillary affinity for the absorbent cord, but tends to remain between the dents when plastic and harden there.

I have shown in Fig. 2 the initial step of manufacturing my improved reed 25 in a standard type of pitch band reed making machine, in which the metal bars or strips, prefer-

ably half round or convexed strips 30 with their flat sides against the dents are substituted for the semi-cylindrical wooden bars employed there-

in and the wax covered cord 28 is substituted for the usual cord employed therein which may be impregnated with wax or equivalent dam material before or after its being helically wound around the bars 30 with a coil 32 thereof between each 30 dent.

It is obvious that the coils 32 between each dent particularly when covered with the wax cover 28 or other covering employed form the flexible resilient dam means 16 interposed between each dent to provide a certain degree of resiliency 40 therebetween.

It is also obvious that in this step of the manufacture of reeds, the dents 12 are made in the usual reed setting machine which feeds the dent wires between the metal strips 30,

cuts each dent wire 12 to the desired length, winds 45 the strand of wax covered yarn so that a coil 32 thereof will be located between each dent wire and so on until a given length of reed is made

and that in the usual manufacture on such a machine the dents 12 will be spaced from each other with the approximate desired spacings. If desired the wax covering 28 may be heated to render it so plastic that it may readily wind during this operation.

I then temporarily space the dents 12 accurately 55 to the desired spacings in the usual manner of making all metal reeds by figuring the correct size of the wire which would cause it to spring when placed on the reed between the dent wires to give the correct number of dents per inch and 60

interpose coils 34 of such coiled wire 36 wrapped around the temporary metal bars 38 between said dents 12 to provide said desired spacings, said coiled wire 36 and side bars 38 being interposed

parallel to said wound cord 32 at spaced intervals 65 across said dents as at 36 and 40, alternate coils being preferably of right and left hand pitch to accurately space the dents, the coils 36 being interposed immediately adjacent the pitch or wax

coils 28 parallel thereto and the coils 40 being 70 conveniently placed substantially centrally of said dents and also parallel thereto. It is obvious, however, that the wax covering 28 of the cord 24

then being plasticized will prevent the dents from temporarily becoming accurately spaced.

Then instead of the old process of making all metal reeds I do not remove the cord coil 24, but retain it as part of the finished reed, whereas in the all metal reed the cord coil would be removed and a metallic spring coil would form the base of the solder receptive well and as will be apparent in accordance with my method the spring coils 36 and 40 are merely temporary and will be removed in the finished article.

10 I then temporarily secure the metallic frame side bars 18 on each side of the ends of said dents beyond said dam means 16 to form solder receiving wells 42 (see Fig. 6) with said side plates 18 forming the side walls thereof and said dam means 15 16 forming the base thereof preferably being spaced somewhat from said side walls to permit the soldering acid to readily boil away therein and yet not spaced sufficiently to permit any substantial amount of solder to run out therebetween. As 20 shown in Fig. 4 said metallic frame side bars 18 are temporarily secured on each side of the ends 23 of said dents beyond said dam means by the wires 44.

Soldering acid is then applied in each well, 25 such as hydrochloric acid, or other type of cleansing and soldering flux, such as now formed of an oil base containing the acid, or any other type of acid or flux employed. If desired the frame end bars 20 are inserted between the projecting ends 30 of the bars 38 and bars 30 and secured thereto by wrapping one end of said bars around said end bars 20, as at 50 (Fig. 5), the portions of said end bars 20 near said dam means bars 30 being also suitably covered with suitable soldering acid or 35 flux.

I then preferably secure by means of wires 47 the flat slabs 49, preferably wooden on each of said reeds so that the ends 51 will terminate at substantially the center portions of said dam means 16 to prevent solder or soldering acid or flux from passing around said dam means 16 to the center portions of said dents. Each side end of said reed 10 is then successively dipped into the molten solder bath 46 up to the ends 51 of 45 said wooden bars 49 and center portion of said dam means 12 to impregnate said well 42 with solder after which the reed 10 may be raised to a position shown in full lines in Fig. 6 in a substantially horizontal plane to cause the solder 48 50 drawn in by said well to substantially fill said well, with said resilient coils 32 of said dam means 16 preventing the soldering acids or solder 48 from passing between the dents to attack the center portions of said dents and with the heat 55 of the solder causing a temporary plastic condition of said plasticizable covering 28 to cause said spacing springs 36 and 40 to temporarily accurately space said dents during the simultaneous hardening of the solder 48 to form with said side 60 and end plates 18 and 20 rigid means 14 to secure the ends 23 of said dents together at predetermined spaced intervals and to said end bars 20 and hardening of said plasticizable acid proof covering 28 to a plasticized condition around 65 said absorbent cord 24 to form resilient means interposed between each dent inside of said rigid joining means. As stated hitherto, I preferably employ as a covering 28 for said cord 24, a plasticizable acid proof material having an intrinsic 70 capillary affinity for said absorbent cord when plastic and I have found that various types of waxes, such as paraffin wax, beeswax, rubber, certain resins, etc. have this highly desirable property. Pitch which I first tried does not, for 75 while it functions admirably as a dam means to

prevent the acid from attacking the center portion of the dents when heated by the solder it tends to run down the center portions of the dents and not having an intrinsic capillary affinity for the absorbent cord will tend to remain 5 and harden there thus making its removal necessary. It is obvious, however, that certain heavy oils, tallow, etc. not strictly plasticizable may be employed if desired.

I then remove the temporary spacing springs 10 36 and 40 with their respective metal bars 38 from the center portions of said dents, and remove the temporary holding wires 44 for the frame side bars and if desired may additionally solder the ends of the metal bars 30 to said frame 15 end bars 20. The dam means 16 may be covered with paper, if desired.

It is thus apparent that I have picked out the best parts of the former method for making pitch band cotton or woolen reeds and the method hitherto employed for making all metal reeds and combined them in a composite process for making a more efficient reed than any hitherto known. I have, however, as stated, modified the usual pitch band into a wax covered band to prevent its running 25 and hardening when plastic and substituted for the usual wooden side bars of the pitch band reed, the metal side bars 30 which will not be affected by the heat of soldering. While it is old to form a pitch band with wooden bars in the manufacture 30 of reeds I believe it is novel to employ wax bands with metal bars in the manufacture of reeds and not only employ them for their inherent purpose of adding resiliency to the reeds as employed in cotton or woolen reeds but also 35 for the additional function of providing a dam means to overcome the most basic fault in the manufacture of all-metal reeds, namely, the running of the acid and the solder to the center portions of the dents through the metal springs hitherto employed for this purpose, which in due 40 course of time, if not completely removed, will corrode the dents. This also additionally eliminates in the manufacture of all-metal reeds the use of any of the objectionable paste hitherto 45 thought necessary for this general purpose. It is also apparent that by my method I am enabled to provide a novel type of all-metal reed in which the dents are accurately spaced and in which they are provided in addition with the resilient 50 means interposed between each dent inside of the the usual rigid joining means near each end thereof to give an added resiliency and flexibility to the dents, preventing the passage of weaving imperfections therethrough and in short provide 55 a better type of all-metal reed manufactured with a lesser number of steps at a minimum cost than hitherto thought possible with this added functional characteristic of increased flexibility due to its inherent structure.

It is understood that my invention is not limited to the specific embodiments shown and that various deviations may be made therefrom without departing from the spirit and scope of the appended claims.

What I claim is:

1. The method of making an improved loom reed which comprises arranging dents in reed form with the approximate desired spacings and interposing resilient plasticizable acid proof dam means between each dent near each end thereof comprising absorbent cord coiled around metal ribs on each side of said dents near each end thereof and with a coil thereof between each dent, impregnated with a plasticizable acid proof mate- 75

rial having an intrinsic capillary affinity for said absorbent cord when plastic, temporarily spacing said dents accurately to the desired spacings by interposing single winds of coil springs of predetermined size between said dents to provide said desired spacings parallel to said wound cord at spaced intervals across said dents and around side bars on each side of said dents, temporarily securing metallic frame side bars on each side of the ends of said dents beyond said dam means to form solder receiving wells between said frame side bars and dam means having the dent ends therein, temporarily securing frame end bars to the end of said spring side bars, treating said wells with soldering acid, and successively dipping each well into a molten solder bath to impregnate said well and cord side bar ends with solder, and raising said reed to a substantially horizontal position to cause said solder to substantially fill said well with said dam means preventing the soldering acid or solder from attacking the center portion of said dents and with the heat of the solder causing a temporary plastic condition of said plasticizable material to cause said spacing springs to temporarily accurately space said dents during the simultaneous hardening of the solder to form with said side and end plates rigid means to secure the ends of said dents together at predetermined spaced intervals and to said end bars and hardening of said plasticizable acid proof material to form resilient means interposed between each dent inside of said rigid joining means to a plasticized condition around said absorbent cord and removing the temporary spacing springs from the center portion of said dents and said temporary securing means for the side and end bars.

2. The method of making an improved loom reed which comprises arranging dents in reed form with the approximate desired spacings and interposing resilient plasticizable acid proof dam means between each dent near each end thereof, inserting temporary spacing means between said dents to accurately space portions thereof to the desired spacings, temporarily securing metallic frame side bars on each side of the ends of said dents beyond said dam means to form solder receiving wells between said frame side bars and dam means having the dent ends therein, treating said wells with soldering acid and successively dipping each well into a molten solder bath to impregnate said well with solder and raising said reed to a substantially horizontal position to cause said solder to substantially fill said well with said dam means preventing the soldering acid or solder from attacking the center portion of said dents and with the heat of the solder causing a temporary plastic condition of said plasticizable material to cause said spacing means to temporarily accurately space said dents during the simultaneous hardening of the solder to form with said side plates rigid means to secure the ends of said dents together at predetermined spaced intervals and hardening of said plasticizable acid proof material to a plasticized condition to form resilient means interposed between each dent inside of said rigid joining means and removing the temporary spacing means from the center portion of said dents and said temporary securing means for the side bars.

3. The method of making an improved loom reed which comprises arranging dents in reed form with the approximate desired spacings and interposing resilient plasticizable acid proof dam

means between each dent near each end thereof, temporarily spacing said dents accurately to the desired spacings by interposing single winds of coil springs of predetermined size between said dents to provide said desired spacings parallel to said wound cord at spaced intervals across said dents, temporarily securing metallic frame side bars on each side of the ends of said dents beyond said dam means to form solder receiving wells between said frame side bars and dam means having the dent ends therein, treating said wells with soldering acid and successively dipping each well into a molten solder bath to impregnate said well with solder, and tilting said reed upwards to cause said solder to substantially fill said well with said dam means preventing the soldering acid or solder from attacking the center portion of said dents and with the heat of the solder causing a temporary plastic condition of said plasticizable material to cause said spacing springs to temporarily accurately space said dents during the simultaneous hardening of the solder to form with said side plates rigid means to secure the ends of said dents together at predetermined spaced intervals and hardening of said plasticizable acid proof material to a plasticized condition to form resilient means interposed between each dent inside of said rigid joining means and removing the temporary spacing springs from the center portion of said dents and said temporary securing means for the side bars.

4. The method of making an improved loom reed which comprises arranging dents in reed form with the approximate desired spacings and interposing resilient plasticizable acid proof dam means between each dent near each end thereof, comprising absorbent cord coiled around metal ribs on each side of said dents near each end thereof and with a coil thereof between each dent impregnated with a plasticizable acid proof material having an intrinsic capillary affinity for said absorbent cord when plastic, inserting temporary spacing means between said dents to accurately space portions thereof to the desired spacings, temporarily securing metallic frame side bars on each side of the ends of said dents beyond said dam means to form solder receiving wells between said frame side bars and dam means having the dent ends therein, treating said wells with soldering acid and successively dipping each well into a molten solder bath to impregnate said well with solder, and tilting said reed upwards to cause said solder to substantially fill said well with said dam means preventing the soldering acid or solder from attacking the center portion of said dents and with the heat of the solder causing a temporary plastic condition of said plasticizable material to cause said spacing means to temporarily accurately space said dents during the simultaneous hardening of the solder to form with said side plates rigid means to secure the ends of said dents together at predetermined spaced intervals and hardening of said plasticizable acid proof material to a plasticized condition around said absorbent cord to form resilient means interposed between each dent inside of said rigid joining means and removing the temporary spacing means from the center portion of said dents and said temporary securing means for the side bars.

5. The method of making an improved loom reed which comprises arranging dents in reed form with the approximate desired spacings and interposing resilient plasticizable acid proof dam means between each dent near each end thereof comprising absorbent wax impregnated cord

- coiled around metal ribs on each side of said dents near each end thereof and with a coil thereof between each dent, temporarily spacing said dents accurately to the desired spacings by interposing 5 single winds of coil springs of predetermined size between said dents to provide said desired spacings parallel to said wound cord at spaced intervals across said dents and around said bars on each side of said dents, temporarily securing metallic frame 10 side bars on each side of the ends of said dents beyond said dam means to form solder receiving wells between said frame bars and dam means having the dent ends therein, temporarily securing frame end bars to the ends of said spring side bars, treating said wells with soldering acid, and successively dipping each well and cord side bar ends into a molten solder bath to impregnate said well with solder, and raising said reed to a substantially horizontal position to cause said solder 15 to substantially fill said well with said dam means preventing the soldering acid or solder from attacking the center portion of said dents and with the heat of the solder causing a temporary plastic condition of said wax to cause said spacing springs to temporarily accurately space said dents during the simultaneous hardening of the solder to form with said side and end plates rigid means to secure the ends of said dents together at predetermined spaced intervals and to said end bars and hardening of said wax to a plasticized condition 20 around said absorbent cord and removing the temporary spacing springs from the center portion of said dents and said temporary securing means for the side and end bars. 25
6. The method of making an improved loom reed which comprises arranging dents in reed form with the approximate desired spacings and interposing resilient plasticizable acid proof dam means between each dent near each end thereof 30 comprising absorbent wax impregnated cord coiled around metal ribs on each side of said dents near each end thereof and with a coil thereof between each dent, inserting temporary spacing means between said dents to accurately space portions thereof to the desired spacings, temporarily securing metallic frame side bars on each side of the ends of said dents beyond said dam means to form solder receiving wells between said frame bars and dam means having the dent ends there- 35 in, treating said wells with soldering acid and successively dipping each well into a molten solder bath to impregnate said well with solder and tilting said reed upwards to cause said solder to substantially fill said well with said dam means preventing the soldering acid or solder from attacking the center portion of said dents and with the heat of the solder causing a temporary plastic condition of said wax to cause said spacing means to temporarily accurately space said dents during 40 the hardening of the solder to form with said side plates rigid means to secure the ends of said dents together at predetermined intervals and hardening of said wax to a plasticized condition around said absorbent cord to form resilient means interposed between each dent inside of said rigid joining means and removing the temporary spacing means from the center portion of said dents and said temporary securing means for the side bars. 45
7. The method of making an improved loom reed which comprises arranging dents in reed form with the approximate desired spacings and interposing resilient plasticizable acid proof dam means between each dent near each end thereof 50 comprising absorbent cord coiled around metal ribs on each side of said dents near each end thereof between each dent, temporarily spacing said dents accurately to the desired spacings parallel to said wound cord at spaced intervals across said dents and around said bars on each side of the ends of said dents beyond said dam means to form solder receiving wells between said frame bars and dam means having the dent ends there- 55 in, temporarily securing frame end bars to the ends of said spring side bars and treating said wells with soldering acid, and successively filling each well with solder with said dam means preventing the soldering acid or solder from attacking the center portion of said dents and with the heat of the solder causing a temporary plastic condition of said plasticizable material to cause said spacing springs to temporarily accurately space said dents during the simultaneous hardening of the solder to form with said side and end plates rigid means to secure the ends of said dents together at predetermined spaced intervals and to said end bars and hardening of said 60 plasticizable acid proof material to a plasticized condition around said absorbent cord to form resilient means interposed between each dent inside of said rigid joining means and removing the temporary spacing springs from the center portion of said dents and said temporary securing means for the side bars. 65
8. The method of making an improved loom reed which comprises arranging dents in reed form with the approximate desired spacings and interposing resilient plasticizable acid proof dam means between each dent near each end thereof, inserting temporary spacing means between said dents to accurately space portions thereof to the desired spacings, temporarily securing metallic frame side bars on each side of the ends of said dents beyond said dam means to form solder receiving wells between said frame side bars and dam means having the dent ends therein, treating said wells with soldering acid, and successively filling each well with solder, with said dam means preventing the soldering acid or solder from attacking the center portion of said dents and with the heat of the solder causing a temporary plastic condition of said plasticizable material to cause said spacing means to temporarily accurately space said dents during the simultaneous hardening of the solder to form with said side plates rigid means to secure the ends of said dents together at predetermined spaced intervals and hardening of said plasticizable acid proof material to a plasticized condition to form resilient means interposed between each dent inside of said rigid joining means and removing the temporary spacing means from the center portion of said dents and said temporary securing means for the side bars. 70
9. The method of making an improved loom reed which comprises arranging dents in reed form with the desired spacings and interposing resilient acid proof dam means between each dent near each end thereof, inserting temporary spacing means between said dents to accurately space said dents to the desired spacings, temporarily securing frame side bar means to each side of the ends of said dents beyond said dam means to form 75

solder receiving wells between said frame bars and dam means having the dent ends therein, treating said dent wells with soldering acid or flux and successively dipping each well into a molten solder bath to impregnate said well with solder and tilting said reed upwards to cause said solder to substantially fill said well with said dam means preventing the soldering acid or flux or solder from attacking the center portion of said dents to form with said side plates rigid means to secure the ends of said dents together at predetermined spaced intervals, said dam means forming resilient means interposed between each dent inside of said rigid joining means and removing the temporary spacing means from the center portion of said dents and said temporary securing means for the side bars.

10. The method of making an improved loom reed which comprises arranging dents in reed form with the approximate desired spacings and interposing resilient acid proof dam means between said dents near each end thereof, inserting temporary spacing means between said dents to accurately space said dents to the desired spacings, securing frame side bar backing means to the ends of said dents beyond said dam means to form solder receiving wells between said frame bars and dam means having the dent ends therein, treating said dent wells with soldering acid or flux and successively filling each well with solder, with said dam means preventing the soldering acid or flux or solder from attacking the center portions of said dents to form with said backing means rigid means to secure the ends of said dents together at predetermined spaced intervals, said dam means forming resilient means interposed between each dent inside of said rigid joining means and removing the temporary spacing means from the center portions of said dents and said temporary securing means for said backing means.

11. The method of making an improved loom reed which comprises arranging dents in reed form with the approximate desired spacings and interposing resilient acid proof dam means between said dents near each end thereof, inserting temporary spacing means between said dents to accurately space said dents to the desired spacings, treating the ends of said dents beyond said dam means with soldering acid or flux and dipping said ends of said dents beyond said dam means into a molten solder bath to impregnate said ends with solder, with said dam means preventing the soldering acid or flux or solder from attacking the center portions of said dents to form rigid means to secure the ends of said dents together at predetermined spaced intervals, said dam means forming resilient means interposed between each dent inside of said rigid joining means and removing the temporary spacing means from the center portion of said dents.

12. The method of making an improved loom reed which comprises arranging dents in reed form with the approximate desired spacings and interposing resilient dam means between said dents near each end thereof, inserting temporary spacing means between said dents to accurately space said dents to the desired spacings, treating the ends of said dents beyond said dam means with soldering acid or flux and dipping said ends of said dents beyond said dam means into a molten solder bath to impregnate said ends with solder, with said dam means preventing the soldering acid or flux or solder from attacking the center portions of said dents to form rigid means to secure the ends of said dents together at predetermined spaced intervals, said dam means forming resilient means interposed between each dent inside of said rigid joining means and removing the temporary spacing means from the center portion of said dents.

13. The method of making an improved loom reed which comprises impregnating an absorbent cord with a plasticizable acid proof material having an intrinsic capillary affinity for said absorbent cord when plastic, arranging dents in reed form with the approximate desired spacings, applying metal ribs on opposite sides of said dents at points equally spaced from each end thereof, helically winding said cord around said ribs with a coil thereof separating each dent to form dam means, inserting temporary spring means between said dents to accurately space portions thereof to the desired spacings, temporarily securing metallic frame side bars on each side of the ends of said dents beyond said dam means to form solder receiving wells between said frame bars and dam means and having the dent ends therein, treating said wells with soldering acid, and successively dipping each well into a molten solder bath to impregnate said well with solder, and tilting said reed upwards to cause said solder to substantially fill said well with said dam means preventing the soldering acid or solder from attacking the center portion of said dents and with the heat of the solder causing a temporary plastic condition of said plasticizable material to cause said spacing springs to temporarily accurately space said dents during the simultaneous hardening of the solder to form with said side plates rigid means to secure the ends of said dents together at predetermined spaced intervals and hardening of said plasticizable acid proof material to a plasticized condition around said absorbent cord to form resilient means interposed between each dent inside of said rigid joining means and removing the temporary spacing means from the center portion of said dents and said temporary securing means for the side bars.
